UNITED STATES PATENT OFFICE.

ALBERT E. PICKARD, OF ROSLYN, NEW YORK.

DESIGN FOR A BOTTLE.

46,066.

Specification for Design.

Patented July 7, 1914.

Application filed April 20, 1914. Serial No. 833,320. Term of patent 14 years.

To all whom it may concern:

Be it known that I, ALBERT E. PICKARD, a citizen of the United States, residing at Roslyn, county of Nassau, Long Island, New York, have invented a new, original, and ornamental Design for Bottles, of which the following is a specification.

In the accompanying drawings Figure 1 is a side elevation of the bottle showing the fluted side; Fig. 2 is a view on the plain or label side of the bottle; Fig. 3 is a top plan view and Fig. 4 a bottom view of the bottle.

The design comprises a cylindrical body integrally connected with a conical top or cap portion, the base of the conical portion being a cylindrical portion of slightly less diameter than the main body portion of the

bottle. The conical top end of the bottle is fluted substantially as illustrated as is also one side of the body portion of the body. As illustrated in the drawings the lower portion of the body is represented as cut away to form legs, the stippled portion in the drawing representing a stopper which closes the lower end of the body and as represented enters between the legs thereof.

I claim:

The ornamental design for a bottle as shown and described.

ALBERT E. PICKARD.

Witnesses:

M. H. LOCKWOOD,
JOHN A. FERGUSON.
